UNITED STATES PATENT OFFICE.

SIMON E. SCHROEDER, OF OAK PARK, ILLINOIS.

WRINGER.

Application filed February 17, 1922. Serial No. 537,144.

My invention has reference to wringers of the type used in connection with washing machines for wringing clothes, and seeks to provide an improved wringer of this character; to lessen the cost of manufacture; to minimize the weight; and to embody same in a more compact and desirable form than wringers which have heretofore been provided.

10 Other objects of my invention are to provide a wringer which may be readily constructed of sheet metal or stamping; to simplify the construction and facilitate assembling; to afford a more desirable location for the tension spring; to house the spring in the base of the wringer; to afford an improved tension release; to permit unlimited separation of the rolls when the tension is released; to mount the upper roll in a frame 20 which is entirely removable from the base or main frame which carries the lower wringer roll; and in general, to provide a wringer which is better adapted for use in connection with power washing machines 25 than wringers heretofore provided.

On the drawings, Fig. 1 is a side view of a wringer embodying my improvement and having parts broken away to disclose details of construction;

30 Fig. 2 a longitudinal vertical sectional view of the wringer shown in Fig. 1;

Fig. 3 a detail view on the lines 3—3 of Fig. 2;

35 Fig. 4 a sectional view on the lines 4—4 of Fig. 2;

Fig. 5 a fragmentary sectional view on the lines 5—5 of Fig. 1;

Fig. 6 a fragmentary sectional view on the lines 6—6 of Fig. 2; and

40 Fig. 7 a sectional view on the lines 7—7 of Fig. 2.

Referring to the drawings, the reference numeral 1 indicates the lower wringer roll and 2 the upper wringer roll, the former 45 of which is journaled in the main frame of the wringer and the latter of which is journaled in a removable frame, which slides into the upper end of the main frame and is held downwardly therein by a spring, so 50 as to afford a yielding tension between the rolls.

The main frame comprises an inverted channel member or base 3, preferably of sheet metal, which is rolled or stamped, so 55 as to have a flat top 4 with a flange 5 along

each side and depending at right angles thereto. Mounted at one end of the channel base 3, is a pair of sheet metal guides 6, which are reversely arranged on opposite sides respectively of the base 3, and each 60 has a plate portion at the lower end extending down along the respective side flange 5 and secured thereto by riveting, as indicated at 7, or in any other suitable manner.

Each guide is formed with a pair of inwardly turned flanges 8 and 9, the latter of which are located at the inner edge of a doubled back portion 10 of the sheet metal, which forms an extension at the side of the flange 9 to embrace the ends of the wringer rolls 70 1 and 2. The flanges 8 are preferably extended downwardly to the lower extremities of the side flanges 5 of the base 3, as shown in Figs. 5 and 6, and these flanges 8 as well as the flanges 9, extend upwardly from the 75 top of the base 3, so as to form guideways into the upper ends of which the ends of the frame which carries the upper wringer roll are slidably engaged. A bearing block 80 11 is placed in the bottom of this guideway upon the top 4 of the base member 3, as shown in Fig. 7, and is secured in place by a bolt 12, which clamps the bearing block 11 between the guides 6 and serves to hold the latter in the required spaced relation. 85

Spaced from the guides 6 and secured to the base 3 in a similar manner, are a pair of guides 13, which have a doubled back portion 14 along the edges similar to the portion 10 of the guides 6, and also flanges 90 15 and 16 similar to the flanges 8 and 9 of the guides 6, but spaced farther apart, as shown in Fig. 4. A bearing block 17 is secured between the guides 13—13 by a bolt 18 so as to leave a gear space 19 between the bearing block 17 and the flanges 16. Each bearing block 11 and 17 has a semi-circular cavity 20 and 21 respectively in the upper end in which the shaft 22 of the lower wringer roll 1 is engaged, said shaft being 100 extended out beyond the guide 13 to receive a driving connection for operating the wringer. The channel member or base 3 is likewise extended beyond the guides 13 and serves to mount the wringer on a support. 105

The frame which carries the upper roll 2 is also preferably formed of pressed or stamped metal and comprises an inverted channel 24, having the ends turned down, as indicated at 25, and provided with a bearing 110

block 26 at each end, secured in place by a rivet 27. Each bearing block projects down below the end of the channel member 24 and is enclosed in a sheet metal housing 28, which is fastened to the bearing block 26 by screws 29, and each bearing block has a bearing slot 30 in the lower end to receive the ends of the shaft 31 of the upper roll 2, said shaft being retained in the bearing slots 30 by the lower walls 32 of the housings 28, which extend across the open lower end of the slot. The housing 28 is of suitable form and size to slidably engage into the open upper end of the guideway formed 10 by the guides 6—6 or 13—13 respectively, the inner flanges 9 and 16 of said guideway being preferably terminated sufficiently below the upper ends of the guideway to facilitate insertion of the upper frame, and the 15 shaft 31 of the upper roll has a gear 33 fixed thereon which meshes with a gear 34, which is fixed on the shaft 22 of the lower wringer roll, these gears being positioned in the gear chamber 19 of the guideway 13—13 20 between the bearing block 17 and the inner-turned flanges 16.

It is necessary for the upper roll 2 to be held at a tension against the lower roll 1, and to accomplish this purpose and also lock 25 the upper frame 24 in the lower or main frame of the wringer, there are plates 35 and 36 respectively at the opposite ends of the wringer frame, the former of which is confined to slide between the bearing block 30 35 11 and the flanges 8 of the guides 6, and the latter of which is confined to slide between the bearing block 17 and the flanges 15 of the guides 13, and these plates 35 and 36 extend upwardly along the ends of the upper frame 34, as shown in Fig. 2, and have 40 perforations 38 engaged by locking rods 39, which latter are mounted in the upper frame 24. These rods 39 are connected at their inner ends to a plate 40 at opposite 45 sides of the stem 41 to which the plate 40 is secured, and this stem extends up through the member 24, the latter being provided with a depending sleeve or bearing 42 for pivotally supporting the stem 41, and the 50 upper projecting end of this stem is provided with a handle 43 for operating the stem 41 and plate 40 to simultaneously project the rods 39 outwardly, as shown by full lines in Fig. 3, or to withdraw same inwardly, as shown by dotted lines in said figure. The outer ends of these rods 39 are loosely mounted in corresponding apertures 44 and 45 of the bearing block 26 and end plate 25 of the member 24, and are adapted 55 60 65 when projected outwardly to engage in the apertures 38 of the plates 35 and 36. The lower ends of the plates 35 and 36 project down below the top 4 of the channel member 3 between the side flanges 5, the top 4 being provided with a slot 46, through

which the plate 36 passes, and each of these plates has a transverse slot 47 at the lower end which is engaged by the respective end of a plate spring 49, which extends lengthwise within the channel member 3. A cap screw 50 is threaded through the spring 49 intermediate of its ends, and engages at its upper end against a bridge 51, which is secured to the under side of the top 4 of the channel member 3, said cap screw being 70 adjustable to regulate the tension of the spring 49 to exert the required downward pull on the plates 35 and 36, to afford the required pressure of the upper roll 2 against the lower roll 1. 75

When the locking rods 39 are released from the apertures 38 of the plates 35 and 36, the latter are pulled downwardly by the tension of the spring 49, somewhat below the ends of the locking rods 39, so that the latter will not readily re-engage therein. To facilitate re-engagement of the locking rods 39 with the apertures 38, I have provided a rod 52, which is mounted in bearings 53 on the under side of the top 4 of the channel member 3, and has a handle 54 projecting beyond the end of the wringer, whereby the rod 52 is rotated in its bearings. This rod projects through a vertical slot 55 in each plate 35 and 36, and is 80 notched at 56 where it passes through each plate 35 and 36, so that the remaining portion of the rod within the notch 55 serves as a cam. When the rod 52 is turned to the position shown in Fig. 2, the notches 56 are at the upper side of the rod and afford clearance between the upper end of the notch 55 and the bottom of the notch 56, so that the spring 49 is free to exert a tension through the plates 35 and 36 on the upper frame 24 and hold the roll 2 down 85 against the lower roll 1. When, however, the rod 52 is turned to the position shown in Fig. 1, the notches 56 are turned downwardly, and the solid portion of the shaft 90 95 100 105 110 115 120 125 130 serves as a cam, which acts against the upper end of the slot 55 and lifts the plates 35 and 36 against the tension of the spring 49, so that the apertures 38 in the plates 35 and 36 are in position to be readily engaged by the ends of the locking rods 39 when the upper frame 24 is set in place in the top of the main frame.

In assembling the wringer, therefore, the shaft 52 is turned to the position shown in Fig. 1, and the upper frame 24 set in place in the top of the main frame with the locking rods 39 withdrawn, as shown by dotted lines in Fig. 3, and after the upper frame is placed in position, the handle 43 is turned so as to project the rods 39 outwardly through the apertures 38, thereby locking the frame 24 onto the upper end of the plates 35 and 36. The rod 52 is then rotated to the position shown in Fig. 2, which releases same

from engagement with the plates 35 and 36 and permits the tension of the spring 49 to be communicated to the upper frame 24 for holding the upper roll 2 down against the 5 lower roll 1.

When it is necessary to release the roll, the handle 43 is merely given a quarter turn movement so that the rods 39 are withdrawn from the apertures 38 of the plates 35 and 10 36, thereby leaving the upper frame 24 free in the upper end of the main frame so that it may be entirely withdrawn or removed 15 from said main frame. The release of the locking rods 39 does not impart any movement or throw to the upper frame 24, as the plates 35 and 36 are merely impelled downwardly by the tension of the spring 49, said downward movement being arrested by stop pins 57, with which the ends of the spring 20 49 come into engagement and these stop pins prevent impact of the plates 35 and 36 against the shaft 52. The upper ends of the plates 35 and 36 are preferably beveled, as indicated at 58, to facilitate insertion of the 25 upper frame, said plates being alike in all respects except that the latter has a vertically elongated slot 59, through which the shaft 22 extends, this slot being sufficiently long to permit the necessary elevation of the 30 upper frame 24 for unrestricted operation of the wringer.

This wringer has a reversible drain board 60 mounted under the lower roll 1, with a flange 61 at each end, having a slot 62 engaged respectively on the pins 63 and 64 carried by the bearing blocks 12 and 17 respectively, the slots being provided so as to permit the drain board to be drawn laterally toward either side of the wringer and 40 tilted downwardly at that side for draining the water from the clothes, as they are passed through the wringer, back into the tub.

This wringer is designed so that the frame parts are constructed almost solely of sheet 45 metal, thereby minimizing the cost of same and affording a light weight structure, and furthermore, the assembling is simplified so as to further reduce the cost of construction and render the parts easily accessible for 50 replacement and repairs. The placing of the spring in the bottom of the wringer frame renders it possible to construct the wringer in a more compact form than wringers heretofore provided, and provides 55 a light upper frame which is easy to handle.

While I have shown and described my invention in a preferred form, I am aware that various changes and modifications may be 60 made without departing from the principles of my invention, the scope of which is to be determined by the appended claims.

I claim as my invention:

1. In a wringer, the combination of a 65 main frame, having a wringer roll mounted thereon, an auxiliary frame movably mount-

ed on the main frame and supporting a wringer roll above the wringer roll on the main frame, a longitudinally extending spring on the main frame below its wringer roll having connectors extending upwardly 70 adjacent the ends of the auxiliary frame, and releasable connections between said connectors and the auxiliary frame whereby the spring acts upon the auxiliary frame to yieldingly hold the wringer roll carried 75 thereby against the wringer roll on the main frame.

2. In a wringer, the combination of a main frame comprising a base with a pair of upwardly extending guides, a wringer 80 roll mounted to rotate on the main frame and extending between said guides, an auxiliary frame slidably mounted in the upper ends of said guides and supporting a wringer roll above the wringer roll on the main 85 frame, a spring in the base of the main frame having connectors extending upwardly adjacent the ends of the auxiliary frame, and releasable means on the auxiliary frame for connecting the latter with the aforesaid spring connectors so that the spring acts on the auxiliary frame to yieldingly hold the wringer roll carried by the latter frame 90 against the wringer roll on the main frame. 95

3. In a wringer, the combination of a main frame comprising a base having a pair of spaced guides extending upwardly therefrom, a wringer roll rotatably mounted on the guides and extending therebetween, an auxiliary frame slidably mounted in the 100 guides and supporting a wringer roll above the wringer roll on the main frame, a spring in the base of the main frame, and having a connector at each end extending upwardly adjacent the respective ends of the auxiliary frame, a handle on the auxiliary frame, and means on the latter frame operable by said handle for releasably connecting the auxiliary frame with the spring connectors so that the spring acts to draw the auxiliary 110 frame downwardly in the guides and yieldingly hold the wringer roll supported by the auxiliary frame against the wringer roll 105 of the main frame.

4. In a wringer, the combination of a main frame having a wringer roll mounted thereon, an auxiliary frame separable from the main frame and supporting a wringer roll above the wringer roll on the main 115 frame, means for detachably connecting the auxiliary frame with the main frame, a spring cooperating with said means to yieldingly engage the wringer roll of the auxiliary frame with the wringer roll of the main frame, and a shiftable member cooperating 120 with the spring for releasing the tension of the spring on the detachable connecting means during the connecting operation of the latter. 125

5. In a wringer, the combination of a 130

- main frame comprising an elongated housing, having a standard at each end, and a wringer roll journaled on and extending between the standards, an auxiliary frame 5 having depending end portions telescoping in the upper ends of the standards, and supporting a wringer roll above the wringer roll on the main frame, a spring in the aforesaid elongated housing, connectors at 10 opposite ends of the spring and extending upwardly adjacent the ends of the auxiliary frame, means for detachably connecting the auxiliary frame to said connectors, and a cam operable to elevate the connectors 15 against the tension of the spring, so as to hold the connectors in position to be engaged by the detachable connecting means of the auxiliary frame.
6. In a wringer, a main frame having a 20 channel like base, a roll supported in said frame, an auxiliary frame slidably supported with respect to the main frame and supporting a roll, a longitudinally extending spring housed in said base, connectors 25 connected with said spring, and means carried by said auxiliary frame for releasably engaging said connectors.
7. In a wringer, a main frame, a roller supported therein, an auxiliary frame slidably supported with respect to the main frame, a leaf spring, means including a pair of connectors for yieldingly engaging said spring and auxiliary frame, and means for controlling said connectors during the engagement of said auxiliary frame with said connectors.
8. A wringer comprising a frame including upright guide portions, a sliding frame guided on the latter, cooperating rollers carried one in each frame, a spring mounted on the frame and operably connected with the sliding frame and means operable at the top of the sliding frame for instantly disconnecting it from the spring.
- 45 9. A wringer comprising a support having upright channeled end members and a base member, a roller journaled in said end members, a cross frame having its ends adapted for sliding movement in the channels of the support, a roller carried by the frame, connectors slidably positioned between the ends of the cross frame and said channels, resilient means for attaching the connectors to said base member, and means 50 carried by said cross frame for releasably connecting its ends to said connectors.
10. In a wringer, in combination, a main frame, a roller supported therein, an auxiliary frame reciprocably mounted in 60 the main frame, a roller mounted in the auxiliary frame, a spring member in the main frame, plates for connecting said spring and auxiliary frame, and quick release means, active through the plates, for effecting optional tensioning or release of 65 tensioning between the rollers in the respective frames, through applied manual force.
11. In a wringer, a frame comprising telescoping frame members having a relative right line sliding movement, rollers supported respectively on each frame member and adapted for contact relation when the frame members are united, resilient means in the bottom frame member, releasable locking means in the top frame member and connector means having one end portion thereof engaging the resilient means and the opposite end engageable with the locking means whereby when the frame members are joined the roller members will be held in contact relation.
12. In a wringer, in combination, a frame comprising telescoping members having a relative right line sliding movement, rollers 75 fixedly supported in each frame member, resilient means in the bottom frame member, connector members engaging the resilient means, locking members on the top frame member and means on said top frame member for actuating the locking members thereon to move them into interlocking engagement with the connector members to effect a releasable interlock between the frame members and to dispose the roller members in contact relation.
13. In a wringer, in combination, a frame comprising telescoping top and bottom members relatively slidable with a right line movement, rollers carried respectively by 80 each frame member, resilient means in the bottom frame member for biasing the rollers toward one another, interlocking means respectively in each frame member one of which is connected to the resilient means and strikable means on the top frame member for actuating the locking means thereon, said interlocking means affecting the joining of the frame members for bringing the rollers into contact relation.
14. In a wringer a substantially U shaped frame comprising a bottom downwardly open channeled member and a pair of vertically extended inwardly open channeled members having their side walls at their lower ends straddling the ends of said bottom member and secured thereto, the side walls of the vertical members having in-turned lips or flanges to provide an open slot in the inner face of each vertical member of less width than the width of the vertical member, bearing blocks vertically slidably mounted in the channels of said vertical members and slidably fitting within said channels and upper and lower wringer rolls supported in said bearing blocks and having their shafts extending through the vertical slots in the vertical members.

15. In a wringer, a substantially U shaped frame comprising a base member and vertically extending channeled members having on their inner faces slots of less width than the channels of the channel members, said channel members being open at their top, bearing blocks vertically slidably mounted in the channels of the vertical members and slidably fitting within said channels, and upper and lower wringer rolls having their 10 shafts extending through said vertical slots and supported in said bearing blocks.

SIMON E. SCHROEDER.
